UNITED STATES PATENT OFFICE.

HENRI BOILEAU, OF BOIS-COLOMBES, FRANCE, ASSIGNOR OF ONE-HALF TO GUSTAVE DEBLADIS, OF PARIS, FRANCE.

PNEUMATIC GUN.

1,405,664.

Specification of Letters Patent. Patented Feb. 7, 1922.

Application filed December 7, 1915. Serial No. 65,558.

(GRANTED UNDER THE PROVISIONS OF THE ACT OF MARCH 3, 1921, 41 STAT. L., 1313.)

To all whom it may concern:

Be it known that I, HENRI BOILEAU, a citizen of the French Republic, residing at Bois-Colombes, Departement de la Seine, France, have invented certain new and useful Improvements in Pneumatic Guns, of which the following is a specification.

The use of compressed gases for throwing projectiles offers certain advantages for shooting at short range, in view of the simplicity of the apparatus and of the ease with which the force used for throwing the projectile is produced. On the other hand, it presents certain difficulties owing to the necessity of effecting at the desired moment a very sudden communication between the gas generator or tank, and the barrel containing the projectile.

On the other hand it may happen that the pressure of the gas to be utilized, suddenly varies, for instance in the case of a compressor placing a tank under pressure, so that it would be very difficult to seize the exact moment when the desired value is reached. It may also happen that, after each shot, the pressure is not brought back to its original value, and varies, whilst still being capable of use for shooting. As the initial velocity given to the projectile, and the range are functions of the pressure, it is necessary in this case, in order to maintain a constant range, to modify the elevation of the gun.

This variation of elevation is also necessary when it is sought to obtain, by trial, a given point of fall. It leads to a loss of time, produces a modification of the angle of fall and requires accurate apparatus, the price of which is out of proportion to the services which are asked from short range guns.

This invention has for its object to bring about automatically the starting of the projectiles when the pressure of the gas reaches a definite value, so that several projectiles can be fired successively to the same point, without modifying the elevation, in spite of possible variations of pressure at the generator. It makes it possible, moreover, to vary at any moment the pressure at which communication is automatically established between the generator or tank and the barrel of the gun, so that the adjustment of the point of fall is obtained without any modifi-

cation of the elevation and of the angle of fall. 55

These results are obtained by inserting, between the barrel and the generator of compressed fluid, an adjustable automatic valve, comprising a balanced or partly compensated valve the sudden opening of which is produced by means of a distributing valve operated by the compressed fluid.

In the accompanying drawing given by way of example,

Figure 1 is a vertical longitudinal section 65 of a pneumatic mortar according to this invention.

Figure 2 is a rear elevation of the same apparatus.

Figure 3 is the same apparatus in firing 70 position.

Figures 4 and 5 are vertical sections of modified constructions of the valve and distributor for the fluid under pressure.

G is the pressure generator, in this case an 75 air compressor driven by a hand wheel. This pump is connected by a union a and a valve v to an intermediate tank R. This tank is provided with a pressure gauge M and is connected by a pipe T to the automatic valve V. The latter, in the construction illustrated, comprises as a main valve, a piston p which, in the position of rest, separates the pipe T and the port L admitting the gases from the valve V to the gun C. 80 On the rod of the piston p are mounted two cylindrical slide valves or piston valves t and s. 85

The pressure of the tank acts behind the slide valve s in the chamber c, owing to the 90 passage of compressed gas through the lateral conduit d, the cross-section of which can be regulated by means of a needle valve e. The pressure exercised on the main valve p is therefore partly compensated by the counter pressure exercised on the piston valve s. 95 A spring f, the tension of which can be adjusted by means of a screw h, is also used as an additional compensator. The spindle of the piston valves s and t is provided with a 100 conduit i which opens between the valves t and s and thus establishes communication between the space comprised between the said valves, and the chamber c arranged behind the valve s. The latter valve, in the position 105 of rest, covers an exhaust port k.

When the pressure in the intermediate tank R increases, the main valve *p* exposed to an increasing force, more or less compensated, according to the proportions of the apparatus and its adjustment, by the counter-pressure exercised on the valve *s*, and by the tension of the spring *f*, will be moved. In its movement, it will gradually move the valves *s* and *t* until the valve *s* uncovers the port *k* and closes the opening of the conduit *d*. At that moment, the pressure falls in the space between the valves *t* and *s*, as well as in the chamber *c*, so that the resistance offered to the movement of the main valve, suddenly becomes very slight. The piston *p* is consequently thrown forward, and quickly uncovers the port *L*, which results in a direct communication being established between the gun C and the intermediate tank R through the pipe T and the conduit *l*.

As soon as the pressure is sufficiently reduced behind the piston *p*, the latter is brought back to its initial position by the spring *f*.

According to the initial compression, or to the position given to the said spring by the said screw *h*, the movement of the piston *p* and of the slide valves will be more or less retarded, and the port *k* uncovered for a different pressure.

Figures 4 and 5 show two other examples of arrangement of the adjustable automatic valve, in which the movements of the slide valves are independent of that of the main valve.

In the example shown in Figure 4, the main valve is constituted by a valve *p* pressed against its seat by an antagonistic spring *r*. The pressure acts under the valve *p* and has the tendency to raise it and to establish direct communication between the gas admission conduit T and the discharge conduit *l* leading to the gun C. The gas passes however through a lateral conduit *d* in a small cylinder containing the slide valves *t* and *s*. The pressure thus acts under the slide valve *t*. It is also established through the conduit *i* between the slide valves *t* and *s*, and through the conduit *j*, in the chamber *c* of the valve *p* which is held on its seat by the said counter-pressure and by the resistance of the spring *r*. The valves *t* and *s* are controlled by an antagonistic spring *f* adjustable by means of a screw cap *h*. An exhaust port *k* is provided in the wall of the cylinder of the slide valves.

When owing to the increase of pressure of the gas under the slide valve *t*, the spring *f* is compressed to a sufficient extent to make the valve *s* uncover the port *k*, the chamber situated above the main valve is emptied, and the pressure under the valve *p* being no longer compensated, the said valve suddenly opens and establishes com-

munication between the tank and the breech of the gun.

As in the preceding arrangement, the regulation of the firing pressure is effected by the screw *h*.

In the modified construction shown in Figure 5, the main valve is constituted by a piston valve *p* with a compensating spring *r*. The slide valve *s* is a piston, the antagonistic spring *f* of which is adjusted by means of the screw cap *h*. The pressure entering through the pipe T passes through a conduit *d* provided in the piston rod and acts on the stem *n*, in the conduit, pushing it up until it uncovers the ports *u* allowing the pressure to enter the main chamber *c* and act on the piston or valve *s* which raises until it in turn uncovers the ports *k* in the valve casing V. As soon as the valve raises above the ports *k*, the upper side of the main valve *p* is released of pressure and consequently is quickly raised off of its seat, and direct communication is established between the intermediate tank and the gun.

An auxiliary hand-controlled exhaust device *o* could be fitted to the valve, by means of which the movement of the main valve could be brought about before its automatic disengagement is obtained by means of the distributors.

The constructions described are given merely by way of example, and the shapes and combination of parts, as well as dimensions, material and applications can be varied, without departing from the scope of the invention.

What I claim as my invention and desire to secure by Letters Patent is:

1. A pneumatic gun comprising a compressed fluid generator, an intermediate storing tank, an adjustable automatic valve between said tank and the breech of the gun, an auxiliary valve for operating the main valve, resilient tensioning means for said auxiliary valve, means for storing pressure under the auxiliary valve and means for releasing the air pressure from under the auxiliary valve when a predetermined pressure has been reached and thereby cause the main valve to open suddenly, substantially as described.

2. A pneumatic gun comprising a compressed fluid generator, an intermediate storing tank, an adjustable automatic valve between said tank and the breech of the gun, an auxiliary slide valve for operating the main valve, an exhaust port normally covered by said auxiliary valve, resilient tensioning means for said auxiliary valve, means for admitting pressure from the tank to the upper side of the auxiliary valve, a conduit through the auxiliary valve to allow the pressure to pass through to the opposite side thereof, a storing chamber below the auxiliary valve

in which the fluid pressure passing through the valve is stored whereby the auxiliary valve is adapted to move to uncover the exhaust port and release the stored pressure 5 in the chamber and thereby cause the main valve to open suddenly, substantially as described.

In testimony whereof I have signed my name to this specification in the presence of a subscribing witness.

HENRI BOILEAU.
